UNITED STATES PATENT OFFICE.

JACOB H. MASKER, OF NEWARK, NEW JERSEY.

IMPROVEMENT IN HAT-BLOCKS.

Specification forming part of Letters Patent No. 39,299, dated July 21, 1863.

To all whom it may concern:

Be it known that I, J. H. MASKER, of the city of Newark, in the county of Essex and State of New Jersey, have invented certain Improvements in Hat-Blocks; and I do hereby declare the following to be a full and exact description thereof, reference being had to the drawings which accompany this specification, making part of the same.

The nature of my invention consists in permanently securing the tongue which keeps the parts of the block in their proper positions on the part to which it is fast in a manner which prevents its ever moving out of place, at the same time keeping the parts of the block from shifting under the ironing process on the hat-body.

In the drawings, Figure 1 is a block in two parts, showing the improved tongue in its position. Fig. 2 is a top view of a block when together. Figs. 3 and 4 show the old manner of the tongue, and Fig. 5 an edge and flat view of a new tongue.

The same letters refer to the same parts in each figure.

In the method in common use the tongue *a* is held by nails, as shown in Fig. 4, and the bottom end of the tongue is made beveling, to accommodate the manner of cutting the groove *b* by rotary cutters, which do not leave the

lower end of the groove square. The beveled ends are shown at *c*, Figs. 3 and 4.

The improved manner of securing the tongue by inserting it in a dovetailed or square-edged groove, as the case may be, is shown at *d*, Figs. 1 and 2. Instead of depending on nails and glue alone, which so often yield to the heat and hard pressure of the smoothing-irons, shifting is rendered almost impossible by inserting the tongue *a* in a groove on each part of the block.

It is desirable to have the block, when put together, come at once to a perfect level on its top, that the iron may not mark the hat in passing over the joint. By making the groove of exactly the same depth in each part of the block and having the lower end, *g*, Fig. 5, of both tongue and groove square, this object is fully attained.

What I claim, and desire to secure, is—

A hat-block made in sections, said sections being united to each other by a wedge or dove-tail formed tongue and groove, the tongue being in line with the base of the block, the tongue and groove terminating before reaching the crown, substantially as shown and described.

Witnesses: J. H. MASKER.
